197,349

TOOTHPICK DISPENSER

Jack L. Most, 3129 Coney Island Ave., Brooklyn, N.Y.

Filed May 6, 1963, Ser. No. 74,754

Term of patent 3½ years

(Cl. D52—2)

Fig. 1

Fig. 2

FIGURE 1 is a perspective view taken from one side and end of a toothpick dispenser embodying my new design.

FIGURE 2 is a perspective view thereof taken from the side and end opposite those shown in FIGURE 1.

I claim:

The ornamental design for a toothpick despenser, as shown.

References Cited in the file of this patent

UNITED STATES PATENTS

D. 63,173	Creazzo	Oct. 30, 1923
609,996	Pond	Aug. 30, 1898
897,789	Schneider	Sept. 1, 1908